RAILWAY JOURNAL LUBRICATOR

James J. Hennessy, New York, N. Y.

Application October 3, 1931, Serial No. 566,776

12 Claims. (Cl. 308—85)

The invention relates to journal lubricating devices and is particularly adaptable for use with locomotive driver journals.

An object of the invention is to provide a simple and inexpensive journal lubricator structure wherein the movement of the journal produces intermittent contact of a lubricating pad with the surface of the journal to effectively lubricate the same.

10 This and other detail objects which will be referred to later are attained by the structures illustrated in the accompanying drawings in which—

Figure 1 is a longitudinal vertical section of one form of the invention showing the lubricating device in the operative position.

Figure 2 is a transverse vertical section taken along the line 2—2 of Figure 1.

Figure 3 is a detail vertical longitudinal section 20 through the device and is taken on line 3—3 of Figure 2.

Figure 4 is a longitudinal vertical section of a modified form of the invention showing the lubricating device in the operative position.

Figure 5 is a vertical transverse section taken along the line 5—5 of Figure 4.

Figure 6 is a detail vertical transverse sectional view of the modified form showing the star wheel and tooth pump operating means.

Figure 7 is a detail horizontal section taken on line 7—7 of Figure 4.

In Figures 1, 2, and 3 the invention is shown applied to a locomotive driver having a hub 1 and a journal 2, the lower portion of which is partly enclosed by a reservoir 3 containing a constantly maintained quantity of lubricant. Reservoir 3 forms the lower part of a common type of journal box positioned between the usual pedestal jaws 4 of the locomotive side frame and 35 yieldingly mounted upon the spacer bar 5 by means of the spring 6 which, while shown as a flat type, may be of any desired type.

A horizontal hollow housing member 7 is provided in the reservoir 3 and extends longitudinally thereof, and is preferably integral therewith and supported by the vertical webs 8. Plunger 9 is received in the housing 7 and has its outer end extending therefrom and through the end wall of the reservoir and provided with a head portion 9a which engages the wheel hub 1. The inner end 9b of the plunger is of reduced diameter and surrounded by the spiral spring 10 which maintains a clearance between the inner end of the plunger and the end wall of the housing and presses the plunger against the face of the wheel hub 1.

Housing 7 is provided on its upper surface and intermediate its ends with an upright hollow neck 11 leading into the interior of the housing. An inverted U-shaped rod 13 has one leg extending downwardly through neck 11 and rigidly engaging plunger 9, and the other leg located outside the neck and provided with a finger 13a substantially at right angles thereto. A vertical lever 14 has a forked end 14a receiving finger 13a and is rigidly connected at its lower end to the end of a round rod 15 which is journaled in a pair of bearing members 16 projecting upwardly from the floor of the reservoir 3.

A horizontal lever 17 of substantial length, paralleling journal 2, is disposed at right angles 15 to rod 15 and is rigidly connected at one end thereto. Lever 17 at the opposite end is pivotally connected to a vertical rod 18 which in turn bears upwardly against a pan 19 disposed beneath the lower surface of the journal and illustrated as comprising a light open framework of wire mesh. Pan 19 is yieldingly supported on springs 21 near each end and carries an oil pad 20, shown as comprising a series of strips, of felt or other porous material which bears against the bearing surface of the journal.

As the journal 2 moves laterally due to play in its bearings, the wheel hub 1 will force the plunger 9 and U-shaped rod 13 to reciprocate in housing 7 and neck 11, respectively, spring 10 maintaining the plunger constantly in engagement with the hub. This movement of the plunger imparts rotation to levers 14, 15 and 17, the latter transmitting the motion through rod 18 to pan 19 and causing oil-soaked pad 20 to be alternately forced against the journal and immersed in lubricant, normally maintained at a level L below pan 19. The length of lever 17 is such as to cooperate with the spring 21 to cause the pad 20, during its upward movement, to slap against the journal, squeezing out some of the absorbed oil.

Neck 12 projects above the level of the lubricant normally stored in reservoir 3 a sufficient distance to prevent the escape of lubricant through the housing 7. Journal wiping members 22 are provided on the upper edge of the reservoir engaging the journal to prevent the lubricant from working longitudinally of the journal beyond the ends of pad 20 and escaping. Splash plates 23 are provided on the pad supporting pan 19 and above the level of the lubricant.

Figures 4 to 7, inclusive, illustrate a modified form of the invention in which the portion of the journal 30 inside the journal box is provided with a tooth-like projection 39. The inner wall 55

of the cellar 32 is provided with a bearing 42 mounting a shaft 33 which carries on its end inside the cellar a cam 34 and on its other end a star wheel 35. Lever 36, pivoted intermediate its ends to an upright element 43 on the floor of the cellar, slidingly engages the face of the cam 34 at one end and is yieldingly connected at the opposite end by means of the bolt 40 and spring 41 to the middle of the pad supporting pan 37. 10 The lever is shown perforated at 45 to accommodate spring 44a which cooperates with spring 44 in maintaining the oil pad normally in engagement with the journal.

As the journal rotates in either direction in its bearings, the tooth projection 39 engages the star wheel 35 and causes the same and the cam 34 to rotate. As lever 36 is engaged by the high portion 34b of cam 34, pan 37 and oil pad 38 will be drawn away from the journal against spring 20 44 and 44a and as the lever engages the low portion 34a of the cam, the springs 44 will cause the pad to forcefully contact with the journal, squeezing out a portion of the absorbed oil, the pad remaining momentarily pressed against the journal 25 to insure adequate lubrication.

In both forms of the invention a predetermined level of the lubricant is constantly maintained in the reservoir by external means, not shown, and is such that when the open-work pan is in 30 its lowest position, the oil pad will be at least partly immersed in the lubricant, thus providing for saturation of the pad at all times. In the highest position of the pan, the pad is pressed against the journal causing lubricant to be discharged thereto. Preferably, the pan supporting springs will be of sufficient strength to cause the pad in its upward movement to slap against the journal, squeezing out a portion of the absorbed oil, thus assuring immediate and adequate 35 lubrication. Or these springs may be just strong enough to support the weight of the pan and pad, the lever mechanism serving to raise as well as lower the pan and pad.

It is apparent that in either of the above forms 45 of the invention wherein either the lateral or rotational movement of the journal is utilized to alternately dip the pad in the supply of lubricant and press the soaked pad upwardly against the journal, positive lubrication of the journal is accomplished with the use of a minimum number of 50 moving parts requiring practically no maintenance or repair. Moreover, the life of the pad is prolonged over previous arrangements wherein constant engagement of a lubricating pad with the journal surface is maintained since the tendency 55 to cake along the bearing surface of the pad is practically obviated and the pad is kept thoroughly saturated at all times. Also, more effective lubrication of the journal is accomplished than has heretofore been possible. In 60 case of damage to the reciprocating mechanism, the oil-soaked pad will be held against the journal continuing the lubrication for a substantial period.

65 While integral structures have been illustrated wherever possible because the consequent increased strength and durability and decreased weight, such parts may be assembled by suitable means where desired. Obviously the various 70 parts may be varied as to shape and size and may be otherwise modified without departing from the spirit of the invention and the exclusive use of the novel features disclosed herein and expressed in the appended claims is contemplated.

75 What is claimed is:

1. In combination, an axle, a journal having an annular shoulder, a lubricant reservoir adjacent said journal, a lubricating pad in said reservoir and movable relative thereto, a plunger 5 slidable through one wall of said reservoir, a spring constantly urging one end of said plunger against said shoulder, and mechanism actuated by said plunger to cause said pad to alternately engage and disengage said journal during movement of the vehicle. 10

2. In combination, an axle, a journal having an annular shoulder, a lubricant reservoir adjacent said journal, a lubricating pad in said reservoir and movable relative thereto, a plunger 15 paralleling said journal and slidably mounted in one wall of said reservoir, said plunger having a head engaging said shoulder, and mechanism connecting said plunger and said pad and arranged to cause said pad to intermittently rise and engage said journal during movement of the 20 vehicle.

3. In combination, an axle, a journal having an annular shoulder, a lubricant reservoir adjacent said journal, a lubricating pad beneath said journal, a spring yieldingly supporting said pad 25 against said journal, a plunger slidable through one wall of said reservoir, a spring constantly urging one end of said plunger against said shoulder, and mechanism transmitting the movement of said shoulder, relative to said reservoir, 30 through said plunger to intermittently lower said pad from said journal into said reservoir.

4. In combination, an axle, a journal having an annular shoulder, a lubricant reservoir adjacent 35 said journal, a lubricating pad beneath said journal, and mechanism transmitting longitudinal movement of said journal, relative to said reservoir, to said pad, said mechanism comprising a plunger paralleling said journal and slidably mounted in an upright wall of said reservoir, a 40 spring constantly maintaining said plunger in engagement with said shoulder, bearing elements projecting above the floor of said reservoir, a rod rotatably mounted in said elements and disposed transversely of said journal, and operative 45 connections between said rod and said pad and said rod and said plunger whereby said rod is caused to rotate in opposite directions and said pad is caused to alternately engage and disengage 50 said journal during movement of the vehicle. 55

5. In combination, an axle, a journal having an annular shoulder, a lubricant reservoir adjacent 60 said journal, a pad under said journal, an elongated housing extending horizontally in said reservoir and beneath the normal level of lubricant 65 therein, said housing having a hollow neck projecting upwardly therefrom above said level, a plunger in said housing, a spring in said housing 70 constantly maintaining said plunger in engagement with said shoulder, and mechanism including elements extending through said neck and engaging said plunger for transmitting longitudinal movement of said plunger relative to said journal to said pad and causing said pad to alternately engage said journal and be immersed 75 in lubricant during the movement of the vehicle.

6. In combination, an axle, a journal, a reservoir adjacent the same, a movable pad in said reservoir, a shaft rotatably mounted in an upright wall of said reservoir, a toothed wheel and a cam rotatable with said shaft, means for rotating said wheel from said journal, and means transmitting rotation of said cam to said pad whereby said pad is caused to alternately engage 75

and disengage said journal during movement of the vehicle.

7. In combination, an axle, a journal, a tooth element projecting therefrom, a lubricant reservoir adjacent said journal, a lubricant pad beneath said journal, a shaft rotatably mounted in a wall of said reservoir, a toothed wheel rotatable with said shaft and operable by said element, a cam rotatable with said shaft and located inside said reservoir, and a lever pivoted to said reservoir, one portion of said lever being operatively engaged by said cam and another portion engaging said pad whereby rotation of said journal causes said pad to alternately engage and disengage said journal.

8. A lubricating device for a railway locomotive driver journal comprising a box-like member for application to the journal between the pedestal jaws and constructed to hold a supply of oil, a rod extending from the interior of said member to the exterior thereof to contact with the hub of the driver, a pad element in said member, and means operated by said rod, as the latter is reciprocated by said hub, to raise and lower said pad to apply the pad to the journal and to lower the pad into the oil.

9. In a railway vehicle, a journal having an annular shoulder, a lubricant reservoir adjacent said journal, a perforated pan in said reservoir and movable relative thereto, a lubricating pad supported on said pan, a spring in said reservoir providing yielding support for said pan and pad, said pad when under the influence of said spring alone engaging said journal, a plunger slidable through one wall of said reservoir, a spring constantly urging one end of said plunger against said shoulder, and mechanism transmitting the

movement of said plunger to said pan and arranged to cause said pad to alternately engage and disengage said journal during movement of the vehicle.

10. A lubricating device for an axle journal comprising a lubricant reservoir arranged to be mounted adjacent the journal, a lubricating pad, yielding means for supporting said pad above the normal oil level in said reservoir and in engagement with said journal, and mechanism operated by the movement of the journal relative to said reservoir and arranged to intermittently depress said pad away from the journal and beneath said oil level and then release said pad.

11. In combination, an axle journal, a lubricant reservoir adjacent the same, a lubricating pad in said reservoir, yielding means normally maintaining said pad in engagement with said journal, and mechanism operated by the movement of said journal relative to said reservoir and arranged to intermittently move said pad away from said journal and into said reservoir and then permit said pad to be returned to its normal position by said yielding means.

12. In combination, an axle journal, a lubricant reservoir beneath the same, an absorbent pad, a spring normally maintaining said pad in engagement with said journal, and mechanism operated by the movement of said journal relative to said reservoir and arranged to intermittently depress said pad beneath the normal oil level in said reservoir and then release said pad permitting the same to be slapped against said journal by said spring to squeeze out a portion of the absorbed lubricant.

JAS J. HENNESSY.
